UNITED STATES PATENT OFFICE.

CARROLL C. STAHL, OF LEMOYNE, PENNSYLVANIA.

CLOSURE FASTENER.

1,404,557.

Specification of Letters Patent. Patented Jan. 24, 1922.

Application filed May 24, 1921. Serial No. 472,030.

To all whom it may concern:

Be it known that I, CARROLL C. STAHL, a citizen of the United States, residing at Lemoyne, in the county of Cumberland and 5 State of Pennsylvania, have invented certain new and useful Improvements in Closure Fasteners, of which the following is a specification.

This invention relates to certain new and 10 useful improvements in closure fasteners and it has for its objects among others to provide a simple and efficient fastener applicable to various uses, so constructed as to do away with a staple and hasp, composed of 15 few parts and those readily assembled, and not liable to get out of order, although capable of manufacture at small cost.

Other objects and advantages of the invention will hereinafter appear, and the 20 novel features thereof will be specifically defined in the appended claims.

The invention is clearly illustrated in the accompanying drawings, which, with the numerals of reference marked thereon, form 25 a part of this specification, and in which—

Figure 1 is a substantially central vertical transverse section showing the invention applied to a lunch box.

Figure 2 is an enlarged section through 30 the parts closely associated with my invention, the latter being shown partly in section and partly in elevation.

Figure 3 is a top plan with a portion of the box shown broken away.

35 Like numerals of reference indicate like parts throughout the several views.

While in the present instance my improvement is shown as applied to a lunch box it is evident that it is capable of use upon other 40 forms of receptacles having a flanged hinged lid.

Referring to the drawings—

1 designates a receptacle, as a lunch box, and 2 its lid or cover hinged as at 3 and 45 provided at its front with a depending flange 4 having in this instance a reinforcing beaded or rolled edge 5.

In constructing the lunch box the front wall is provided with two openings 6 and 50 7, and the flange of the lid with an opening 8 adapted to register with the opening 6 in the front of the box, as seen in Figures 1 and 2.

To the rear face of the front wall of the 55 box is affixed by solder or otherwise the support for the fastener. This support may

be, as herein shown, of a single piece of material bent to form the front piece 9, the rear piece 10, the parallel side pieces 11 and 12, the partition 13 and the member 14 connecting the front piece 9 with the said partition at its junction with the side 12, as shown in Figure 3, although it may be formed of more than one piece if preferred, the result being the same. The rear wall 60 10 and the said partition 13 are provided with openings 15 and 16 respectively, in alignment with the openings 6 and 8 in the front wall and the flange of the lid as seen in Figure 2.

The locking member comprises a rod or wire having one end beveled as seen at 17, the arm of the locking member having such beveled end being slidably mounted in the openings in the front 70 wall of the box, an opening 18 in the front piece 9, and the openings in the rear piece and the partition as seen in Figure 2, the said arm being numbered 19. After passing rearward through the opening 15 80 the locking member is bent at right angles to the said arm as seen at 20, and then again at right angles to said member 20 to form the arm 21 which extends through the opening 7 in the front wall of the box as seen 85 best in Figure 2.

22 is a spring around the arm 19 between the rear piece 10 and the partition 13, with one end abutting the said rear piece and the other end engaged in one of a series of 90 openings 23 in the arm 19, whereby the tension of the spring may be adjusted as occasion may require or as may be required according to the thickness of the depending flange of the lid.

95 In use, the parts being as shown, if the lid is lowered, the bottom edge of the flange 4 will strike and ride over the beveled end of the arm 19, forcing the same rearward till the flange has reached its proper closed position, when the spring will force the said arm forward and its beveled end will engage in the opening 8 in the front wall of the box and the lid will be secured in the closed position. When it is desired to open the lid, 100 pressure on the extended end 24 of the arm 21 will force the same inward and consequently the beveled end of the arm 19 till the same is out of the opening 8 in the flange when the lid can be raised. The fastener is 105 automatic in its locking movement.

Modifications in detail may be resorted to

without departing from the spirit of the invention or sacrificing any of its advantages.

What is claimed as new is:—

1. A closure fastener attachable to the inner face of a wall of a receptacle, and comprising rear and side walls and an intermediate partition, and a spring-actuated fastener having one member movable through openings in the said rear wall and partition and adapted for passage through a coincident opening in a wall of a receptacle.
2. A receptacle, and a hinged lid therefor having a depending flange with an open-

ing, the front wall of the receptacle having a coincident opening and a second opening, 15 combined with a member attached to the inner face of the front wall of the receptacle and having a locking member comprising a bolt with a beveled end and a member parallel with the said bolt and extended beyond 20 the front wall through the opening therein, and a spring acting on said bolt to project the same to force its beveled end into the opening in the flange of the lid.

In testimony whereof I affix my signature. 25

CARROLL C. STAHL.
